UNITED STATES PATENT OFFICE.

RICHARD B. BROWNE, OF BROOKLYN, NEW YORK.

CASEMENT-WINDOW.

1,199,868.

Specification of Letters Patent.

Patented Oct. 3, 1916.

Application filed August 5, 1915. Serial No. 43,776.

To all whom it may concern:

Be it known that I, RICHARD B. BROWNE, a citizen of the United States, residing at Brooklyn, New York, have invented certain 5 new and useful Improvements in Casement- Windows, of which the following is a specification.

One of the objects of the invention is to provide, in connection with a casement window, a substantially full opening and to permit the sash glasses to be washed on both sides from within the apartment in which the window is installed.

Another object is to provide in connection 15 with vertically arranged sashes, improved supporting and guiding means therefor.

A further object is to construct and arrange the sash controlling operating linkage to support the weight of the sashes.

20 A further object is to provide improved means for retaining the sashes in various open positions and for locking them in closed position.

Other objects and advantages of the invention will be sufficiently described hereafter in connection with a detailed description 25 of the accompanying drawing, which shows the best form of the invention which has up to the present time been devised. 30 It is to be understood, however, that the invention is capable of embodiment in other forms, and I do not limit myself to details except as claimed.

Figure 1 is an elevation of a window embodying the invention, the point of view being from the side of the window, which is usually the inside, according to the preferred manner of placing the window in a building. Fig. 2 is a side elevation of the same, with 40 the sashes in partly open position. Fig. 3 is a top plan of the same. Fig. 4 is a horizontal section, enlarged, on the line 4-4 of Fig. 2. Fig. 5 is a vertical sectional detail of the handle and latch mechanism. Fig. 6 is a 45 fragmentary enlarged elevation of one of the common link pivots. Fig. 7 is a vertical detail of the top part of a sash and frame particularly showing weatherproofing features. Fig. 8 is a sectional detail at 8-8, 50 Fig. 1. Fig. 9 is a sectional detail of the bottom part of the frame of one of the sashes showing a part of the retaining means for holding the sashes in various open positions. Fig. 10 is a detail of another part of the 55 sash-holding means.

The frame F comprises side members, f,

sill f' and lintel f''. A substantially central mullion M is also usually provided. The sashes S, S' are hinged together at their meeting edges at 11. The free edges of the 60 sashes at top and bottom move in close proximity to beads 12 provided on the sill and lintel. In some cases the edges 13 of the sashes proper may engage or move in close proximity to these beads. In other cases, 65 other members, later to be described, may have such engagement with or proximity to the beads.

At a suitable place or places, usually near the top and bottom of the window, are provided combined guiding and supporting links or arms 14. These arms are arranged in pairs and of each pair the inner ends are connected or hinged at a common point 15, usually located upon the mullion. The 75 outer ends of the links of each pair are pivoted at 16 to the sashes, midway between their outer edges and the hinge point 11. At different points in their length the arms 14 are made of suitable vertical dimensions to 80 properly support the weight of the sashes. As seen in Figs. 1 and 6, near the common hinge point 15, the arms have relatively great depth, and the length of the hinges is also suitable for the proper support of the 85 weight imposed upon them. The arms may be reduced in vertical dimension as they approach the sashes.

The arms, sashes and pivot connections are suitably designed so that as the sashes 90 are moved their hinge connection 11 moves in a line perpendicular to the horizontal center of the frame; that is, along a line perpendicular to the frame at the point 15, while the free edges of the sashes move in 95 the same straight line along or close to the beads 12. Thus when the sashes are fully opened they lie close together and approximately perpendicular to the frame at the center thereof. In closing, the sashes move 100 uniformly in relation to each other and to the frame, until when fully closed they are in line with each other and the window opening is completely closed.

To insure the proper motion of the sashes, 105 it is essential that the parts of the linkage (including in this term the sashes themselves) shall conform to requirements of a movable parallelogram; that is, each of the links and the part of the sash opposite to it, 110 between the point 16 and the point 11, should be parallel and of the same length,

and the part of the sash between the point 20 and the point 16 should be of the same length. The point 15 and the parts of the sashes that are in proximity to the beads 12 should also be in line at all times. To produce this result, the hinge pins 15 are located substantially in a line with the outer faces of the beads 12 and parts of the mullion at 17 are cut away to accommodate the arms 14 when the window is closed. The pins of hinges 16 are also recessed into the sashes so that they are directly in line with the free edges of the sashes and the hinge pins 11. The hinge points 16 are also carefully located midway between hinges 11 and the free edges of the sashes. Eyes 18 on arms 14, which engage the pins of hinges 16, are also offset or arranged at one side of the arms so that when the window is closed the arms may lie parallel to and against the sashes.

It will thus be understood that in all the movements of the sashes the linkage, comprising the arms 14, properly guides the sashes and at the same time the arms entirely support the weight thereof so that no part of the sashes engages frictionally with any part of the frame. The sash movement is therefore exceedingly free and accurate. At the same time in most positions the sashes are self-braced against wind pressure and especially lateral wind pressure. To prevent accidental movement of the sashes, as for instance by wind pressure when the sashes are in approximately the position of Fig. 4 or between that position and the fully closed position, especial means may be provided.

One or both of the sashes at top or bottom, but usually at the bottom, is provided with a holding member 20 and this member is usually yieldable. For this purpose the member 20 may be bolted or otherwise secured to the edge of the sash at 21 and may be free from the sash for a suitable distance at 22. By the use of a suitable tool this free part of the holding member may be bent outwardly slightly to bring it into proper relation to bead 12 or to the movable latch or detent. This detent is a strip 23 hinged to bead 12 at 24 and provided with serrations or notches 25 to coöperate with the yieldable end of holding piece 20. When the sashes are in proper position detent 23 is swung up from the position of Fig. 9 and into engagement with holding piece 20 and thus the sashes are positively locked in position and secured against any accidental movement due to wind pressure or other cause. If any looseness develops as between the detent 23 and the holding member 20 it may be taken up by slightly bending out the free portion of the holding member.

A suitable latch is provided for holding the window in closed position, and this is

preferably combined with an operating handle. For this purpose, in a preferred embodiment, a bolt 26 is movably mounted in the mullion and urged to active position by spring 27. The operating handle 28 is pivoted to one of the sashes and is also provided with a latch 29 to coöperate with bolt 26. When the sashes are partially closed, the handle may be easily grasped and by pulling it straight in the sashes are fully closed, and then by moving the handle laterally latch 29 is engaged with bolt 26 and the window is securely locked against opening from the outside.

Suitable weatherproofing features are provided as follows: Along their meeting edges one of the sashes is recessed as at 30 and the other is provided with a bead or flange 31 to enter the recess. A strip of felt 32, or other suitable packing, is also placed along the edge of one of the sashes to be engaged by the other and complete the weatherproofing along the vertical meeting edges.

The lintel f^2 is provided with a drip strip 33 extending out beyond the sashes when they are closed. A strip of packing 34 is also carried by the lintel or top frame member to be engaged by flanges 35 on the sashes when closed. The sashes on their upper edges may further be provided with a weatherstrip 36 of metal or other flexible material to engage the vertical web of the frame member when closed. This weatherstrip serves to carry off to the sides of the sashes any water which may get between the lintel 100 and the sashes.

At the bottom the sashes have a flange 38 to coöperate with a suitable recess in the sill and the lower edges of the sashes are also provided with strips 39 to engage beads 12 105 or packing 40 carried thereby.

The vertical members of the frame are usually of channel section and at the bottom of the channels are located packing strips 41, and these are engaged by free edges 13 110 of the sashes. The outer faces of the sashes are recessed at 42 to avoid interference between this part of the sash and the flange of the frame member in the first part of the opening movement. This is quite important because evidently the first opening movement of the sashes causes an outward movement adjacent to the points 42, and without suitable recessing there would be more or less interference with the frame at 120 this point.

The organization above described, and particularly the structural details thereof, are evidently especially adapted to metal windows, but evidently most of the features described and all of the principal features of the invention are adaptable to wooden or composite structures of various kinds. The organization described is also especially adapted to sashes arranged vertically, but I 130

contemplate the use of the window with reference to the arrangement vertically in some cases and do not limit myself to certain cases and do not limit myself to such features as are especially adapted for that purpose.

In view of the possibly different arrangements of the window, it will be understood that such words as "top," "bottom" and 10 "sides" are used for comparison or to indicate relative position of parts of the frame or sashes.

In addition to serving as holding members 15 coöperating with the hinged detents 23, the members 20 may coöperate with beads 12 to guide the free edges of the sash along the beads in a straight line and any play or clearance between the sashes and the beads may be taken up as much as is desired by 20 the adjustable feature of said members 20, as previously described. When the detents 23 are provided, therefore, the members 20 perform the double function of guiding and holding members as described.

25 In some cases it is desirable to provide a stop 45 which, in the present embodiment, is secured to one of the beads 12 to engage one of the sashes and limit the opening movement thereof so that in opening the sashes 30 they will not approach each other too closely. If the sashes are permitted to stand too close together when in the closed position lateral pressure applied to them might in some cases strain 35 or deform the linkage or produce other undesirable results.

7. *Claims*

8. In a window, the combination of a frame, two sashes hinged together at their meeting edges and links pivoted together in 10 the frame at a common point and having their outer ends pivoted to the sashes, the links being constructed and arranged to support the weight of the sashes and at the same time guide them to fold uniformly to 15 gether toward the center of the frame in the opening movement.

9. In a window, the combination of a frame, two sashes arranged therein and hinged together at their meeting edges and 20 guiding arms pivoted together at a common point and having their free ends pivoted to the sashes at the centers thereof, said arms and sashes being constructed and arranged so that the sashes are positively guided to 25 fold together toward the center of the frame and to stand approximately perpendicular and to stand approximately in line and parallel to the sash-arms when closed, the sashes being 30 substantially parallel to the frame when closed.

10. In a window, the combination of a frame, two sashes hinged together at their meeting edges, links having a common pivot and also pivoted to the sashes at the outer ends of the sashes, the links being 35 intermediate the frame and between the sashes,

said holding means and links serving to hold both of the sashes positively in different intermediate positions when said holding means is in active position.

4. In a window, the combination of a frame, two sashes hinged together at their meeting edges and links pivoted in the frame at a common point and pivoted at their outer ends to the sashes, the links being constructed and arranged to guide the 75 sashes to fold uniformly together toward the center of the frame in the opening movement.

5. In a window, the combination of a frame having a bead along one side thereof, two sashes hinged together at their meeting edges and having their free edges located close to said bead, one or more pairs of supporting arms, each pair being pivoted at a common point substantially in line with said free edges of the sashes, the outer ends of said arms being pivoted to the sashes midway between the inner and outer edges thereof.

6. In a window, the combination of a frame having a bead along one side, two sashes hinged together at their meeting edges and having their free edges arranged to run close to the bead, one or more pairs of supporting arms, the arms of each pair being connected to the frame at a common point in line with the free edges of the sashes by a long hinge member, the outer ends of said arms being pivoted to the sashes midway between the inner and outer edges thereof.

7. In a window, the combination of a frame having a bead along one side, two sashes vertically arranged in the frame and hinged together at their meeting edges, a center mullion in the frame, long hinge members at top and bottom of the mullion and two pairs of arms, the arms of each pair being connected to one of the sashes members and the outer ends of the arms being pivoted centrally to the sashes, the arms being relatively deep vertically near the common hinge points to enable them to carry the weight of the sashes.

8. In a window, the combination of a frame, vertical sashes hinged together at their meeting edges, supporting arms pivoted in the frame at a common point, hinge pins at the centers of the sashes and in line with the sash-hinge-connection and the free 100 edges of the sash and hinge-edges at the outer ends of the arms connected with said hinge pins, said hinge-pins being offset upon the sashes.

9. In a window, the combination of a frame, two sashes hinged together at their meeting edges, links having a common pivot and also pivoted to the sashes at the outer ends of the sashes, a holding piece at the outer edge of one of the sashes and a hinged pivot plate 105

carried by the frame and provided with notches to engage said holding piece to positively hold the sashes in different positions.

5 10. In a window, the combination of a frame, two sashes hinged together at their meeting edges, and an arm for each sash pivoted to the frame and to the sash to support and guide the latter, so that in closing the window the sashes move toward an alined position, and in opening the window the sashes fold toward an approximately parallel position.

11. In a window, the combination of a frame, two sashes hinged together at their meeting edges and an arm for each sash pivoted thereto, said arms being pivoted to the frame at a common point to guide the sashes in definite relation to the frame, so that in closing the window the sashes move toward an alined position, and in opening the window the sashes fold toward an approximately parallel position.

12. In a window, the combination of a frame having a bead, two sashes hinged together at their meeting edges and having their free edges adjacent to the bead, and guiding arms pivoted in the frame at a common point and pivoted to the sashes to cause the sashes to fold in definite relation to the frame and to cause the said free edges of the sashes to move in a straight line along said bead.

13. In a window, the combination of a frame, a bead along one side thereof, sashes hinged together at their meeting edges and supporting and guiding arms hinged in the frame at a common point along said bead, the outer ends of the links being pivoted to the sashes midway between the hinged and free edges thereof whereby the hinged edges of the sashes are caused to move perpendicular to the frame and the free edges of the sashes are caused to move in a straight line along the bead in folding.

RICHARD B. BROWNE.
